JOHN WILLIAM SMITH, OF SYRACUSE, NEW YORK

FUEL-MIXING DEVICE

Application filed May 16, 1929. Serial No. 363,632.

This invention relates to mixing devices in general and more especially to mixing devices for mixing air with fuel for use in furnaces, internal combustion engines and the like.

5 The present invention aims not only to provide a device which is suitable for mixing air with gasoline for use in an internal combustion engine but also air with oil, or air with powdered fuel such as powdered coal and the like.

10 Among the objects of the present invention it is also aimed to provide an improved construction of mixing conduit composed of two main units which nest into one another and form not only the mixing element but also the conduit itself.

15 These and other features, capabilities and advantages of the invention will appear from the subjoined detail description of one 20 specific embodiment thereof illustrated in the accompanying drawings in which

Figure 1 is a plan view of a mixing device made according to the present invention;

25 Fig. 2 is a side elevation of the same; and Fig. 3 is a section on the line 3—3 of Fig. 2.

In the embodiment illustrated, there are provided two main casting members 1 and 2 respectively which are complements of one another. The members 1 and 2 are substantially half portions of a conduit which are adapted to be secured to one another to form a conduit. To secure the two sections to one another, the member 1 has an elongated flange 3 on one side thereof to register with the elongated flange 4 on the member 2 and which are provided with alined recesses 5 and 6 respectively to receive the bolts 7. The other side of the member 1 is similarly provided with an elongated flange 8 which registers with and engages the flange 9 of the member 2, and these flanges 8 and 9 are provided with alined openings 10 and 11 respectively to receive the bolts 12.

30 The ends of the sections 1 and 2 form with one another the cylindrical portions 13 and 14 which are provided with the external threads 15 and 16 respectively to receive suitable couplings, not shown, to connect the resulting mixing conduit by connecting the end 15 with a suitable air and fuel supply and

the end 16 with the furnace or engine to be supplied with the fuel.

The sections 1 and 2 have the wall members 17 and 18 respectively which are spaced from one another a distance less than the diameters of the ends 15 and 16, and have a greater width than the diameters of the ends 15 and 16, substantially twice the diameters of the ends 15 and 16.

35 Each of the wall members 17 and 18 have formed thereon a series of interceptor blades which preferably interlace with one another, as indicated in the drawings, the wall 17 having formed thereon a plurality of rows 19 of interceptor blades and the wall 18 having formed thereon a plurality of rows 20 of interceptor blades. The interceptor blades of the rows 19 and 20 are substantially identical in dimension and form, the number of blades to each row being preferably the same.

40 Each blade 21 consists of a base triangular in form having a front side 22 in alinement with the front side of the adjacent blade 21 of the row, the front sides 22 of a row of blades being preferably a straight line extending transversely of the wall members 17, 18. The front face 23 of each blade is substantially a triangle bounded by the edges 24 and 25 which converge to form the apex 26, the termination of the rear edge 27 of the blade 21, which rear edge 27 forms with the edge 24 a lateral triangular face 28 and with the edge 25 a lateral triangular face 29.

45 The lower end of the rear edges 27 of the blades 21 of each row are in alinement with one another and preferably terminate on the line in alinement with the lower front edges 22 of the succeeding row of interceptor blades. The apices 26 of each row of interceptor blades 21 are preferably in alinement with one another extending transversely of the walls 17, 18, which line of apices is preferably, as illustrated, disposed a short distance in advance of the transverse line passing through the lower edges 27 of the blades 21. The blades of the row 20 directly opposite to the blades of the row 19 are substantially identical in dimension and form, see Fig. 2.

50 For convenience of description, we will

designate the blades of the row 20 as 21^a to distinguish them from the blades 21 of the row 19.

The blades 21 of the row 19 extend into the spaces formed between adjacent blades 21^a of the row 20 to interlace with one another and, as clearly illustrated in Fig. 2, the apices 26 of the blades 21 are spaced a short distance from the inner face of the wall 18, and similarly the apices 26 of the blades 21^a are disposed an equally short distance from the inner face of the wall 17. As clearly appears in Fig. 2, the front faces 23 of the blades 21 extend beyond the middle of the blades 21 with the apices 26 terminating in a line beyond the middle of the blades 21 and just a short distance in front of a plane passing through the inner ends of the rear edges 27 of the blades 21.

The walls 17, 18, forming the conduit, are provided with a series of successive rows 19 and 20 of interceptor blades 21 and 21^a respectively disposed one immediately adjacent to the other, substantially the entire length of the conduit formed by the walls 17 and 18.

With this form of mixing conduit, certain definite physical forces are exercised on a stream or mixture flowing through the conduit from the end 15 to the end 16. In order to have a definite mixture before us, let us assume, for instance, that the mixture is a mixture of oil and air for an oil burner. In such case, it is desirable that the oil be subdivided into the smallest particles possible so that it will form a veritable mist with the air with which it is being fed through the conduit. It has been found that the oil particles assume the form of small globules. These globules can be broken up into smaller parts by being forced against an obstruction by impact. This is done by causing the globules to strike against the front faces 23 of the blades 21 and 21^a. Next, it has been found that these globules can be further divided into smaller parts by a shearing action when caused to move along a sharp edge. To this end, the forwardly inclining edges 24 and 25 of the faces 23 form shearing edges so that the globules moving along these edges will be caused to be sheared off into small particles. Due to the fact that the stream is rushing on in the direction of the end 16, the small globules striking each face 23 will sooner or later be caused to pass over such shearing edge or over the apex 26 which will of course form a similar shearing action. Furthermore, it has been found that when the natural fluctuation of the stream as it passes from one end of the conduit to the other is exaggerated to form a wave motion of considerable amplitude, the resulting change of pressure embracing a succession of changes from high pressure to low pressure and back to high pressure will aid in reduc-

ing the stability of the globules so that they can be readily separated into finer particles by the impact faces 23 and shearing edges 24 and 25.

This action of successive changes of pressure from high pressure to low pressure and back to high pressure is induced by the particular form of the blades 21 having the broad faces 23 opposing the movement of the stream with receding faces terminating in the rear edge 27 diverging from the path of movement of the stream to form an area of low pressure. This area of low pressure of course is intensified by the fact that not only the blades 21 of the row 19 have such receding faces but likewise the opposing blades 21^a of the row 21 are similarly constructed with receding rear faces.

This wave action is further exaggerated by causing the particles of the stream to move from one row of blades 21 to the other row 19 of blades 21^a and back to the other row 20 of blades, and back again to the succeeding row of blades and so on so that the wave action is not only in a longitudinal direction consisting of successive alternate periods of compression and rarefaction but also in a lateral direction consisting of successive alternate movements from the right to the left. This wave action is further accentuated by the interlacing of the blades of each row with the blades of the opposite row so that the portion of the stream passing the area determined by two opposing rows 19 and 20 of blades consist of a plurality of independent streams of matter moving in a plurality of different waves which overlap one another.

It is obvious that various changes and modifications may be made to the details of construction without departing from the general spirit of the invention as set forth in the appended claims.

I claim:

1. A mixing device of the character described composed of two horizontal sections forming a conduit, each section having formed thereon a plurality of rows of interceptor blades, the rows of blades of each section opposing one another and interlacing with one another, the blades having impact faces and receding rarefaction creating faces.

2. A mixing device of the character described consisting of two sections secured to one another and forming a conduit, each section having formed thereon a plurality of rows of interceptor blades, each interceptor blade consisting of a triangular front face and two triangular rear faces, the blades of each section opposing the blades of the other section and interlacing with one another to form successive alternate areas of compression and rarefaction.

3. A mixing device of the character described consisting of two sections secured to

one another and forming a conduit, each section having formed thereon a plurality of rows of interceptor blades, each interceptor blade consisting of a triangular front face and two triangular rear faces, the blades of each section opposing the blades of the other section and interlacing with one another to form successive alternate areas of compression and rarefaction, the front edges of the bases of the blades of each row being disposed in a line transversely of the sections.

4. A mixing device of the character described consisting of two sections secured to one another and forming a conduit, each section having formed thereon a plurality of rows of interceptor blades, each interceptor blade consisting of a triangular front face and two triangular rear faces, the blades of each section opposing the blades of the other section and interlacing with one another to form successive alternate areas of compression and rarefaction, the apices of the blades of each row being disposed in a line transversely of the sections.

5. A mixing device of the character described consisting of two sections secured to one another and forming a conduit, each section having formed thereon a plurality of rows of interceptor blades, each interceptor blade consisting of a triangular front face and two triangular rear faces, the blades of each section opposing the blades of the other section and interlacing with one another to form successive alternate areas of compression and rarefaction, the front edges of the bases of the blades of each row being disposed in a line transversely of the sections, the apices of the blades of each row being disposed in a line transversely of the sections.

6. A mixing device of the character described consisting of two sections secured to one another and forming a conduit, each section having formed thereon a plurality of rows of interceptor blades, each interceptor blade consisting of a triangular front face and two triangular rear faces, the blades of each section opposing the blades of the other section and interlacing with one another to form successive alternate areas of compression and rarefaction, the apices of the blades of each row being disposed in a line transversely of the sections and to the rear of the middle of the blades of each row.

7. A mixing device of the character described consisting of two complementary castings secured to one another to form a conduit, the sections forming cylindrical ends and having external threads thereon, the intermediate portions of the sections being wider than the diameters of said ends and spaced apart a distance less than the diameter of said ends, each section having formed thereon a plurality of rows of interceptor blades, each interceptor blade consisting of a triangular front face and two triangular rear

faces, the bases of the triangular front faces of each row extending in a line in the inner face of each section and transversely to such section, each row of blades in one section being disposed opposite to a row of blades in the other section, each blade of a row on one section extending into the space formed between two adjacent blades in the row of the other section.

8. A mixing device of the character described consisting of two sections secured to one another and forming a conduit, each section having formed thereon a plurality of rows of interceptor blades, each interceptor blade consisting of a triangular front face and two triangular rear faces, the tapered portion of each blade of a row on one section extending into the space formed between two adjacent blades of an opposite row on the other section, the resulting interlacing blades forming successive alternate areas of compression and rarefaction.
